United States Patent Office.

JAKOB HUSNIK, OF TABOR, AUSTRIA, ASSIGNOR TO HEINRICH POLLACK AND ALBERT EDWIN SCHMIDT, OF HAMBURG, GERMANY.

Letters Patent No. 95,353, dated September 28, 1869.

IMPROVEMENT IN ROTATING HOOK FOR SEWING-MACHINES.

The Schedule referred to in these Letters Patent and making part of the same.

I, JAKOB HUSNIK, of Tabor, in Bohemia, Austria, have invented a new and useful Rotary Hook for Sewing-Machines.

Nature and Objects of the Invention.

My invention relates to rotary-hook sewing-machines, and consists in a device which prevents such deflection of the needle as will endanger injury to either the hook or the needle by one of them coming in contact with the other in use.

In order to prevent the deflection of the needle across the path or plane of the hook, I form upon the rear extremity of the hook a projection or "tail," which, though in the same plane as the point of the hook, is so much nearer the centre that it does not interfere with the formation of the loop or the entering of the same by the point of the hook. The said tail projects rearward, beyond the point of the hook, so that it will afford a lateral bearing for the needle-point until the point of the hook has crossed the face of the needle in entering the loop.

Description of the Drawings.

In the accompanying drawings—

Figure 1 is a front view of my improved rotary hook, showing also the position of the needle, the point of the hook being represented as just entering the loop.

Figure 2 represents a longitudinal elevation of the hook in the same position.

Figure 3 is a plan or top view thereof.

Figures 4 and 5 are, respectively, a front and a top view of the rotary hook, as commonly constructed.

Similar letters of reference indicate corresponding parts in the several figures.

General Description.

The main body B of the hook, with its point b, may be constructed as usual, and mounted upon a shaft, A, in customary manner.

T represents a tail or projection, formed upon the rear part of the hook, nearer the axis than the point

b, and projecting backward beyond the said point, as clearly shown in fig. 1, so as to protect and form a lateral support for the needle until after the point b has crossed its face, so that it is impossible for the point of the rotating hook to pass behind or against the needle N, or for the latter to be so deflected, by pulling of the fabric in sewing, that it will be caused to strike upon the hook in its descent.

From an inspection of figs. 4 and 5 of the drawings, which figures represent the rotary hook as now usually constructed in the Wheeler & Wilson sewing-machines, it will be evident that the unprotected needle N is liable to deflection by the drawing of the fabric to assist the feed, which is necessary with some kinds of work, as, for instance, in sewing very thick seams, and is frequently practised by users of the machine when it is unnecessary. This deflection of the needle causes it to descend within or across the path or plane of the hook, and hence results in breaking of needle or thread, or both, or in the scratching and injury of the hook or bobbin, or in all of these evils combined.

By use in inexperienced hands, or by reason of irregularity in the bend of the needle, it very often happens that the best finished sewing-machines are quickly put out of order by interference between the hook and needle, so that they are necessarily returned to the machinist to have the roughness ground off the hook and bobbin, and both repolished, in order that they may work without breaking the thread.

My invention thus avoids annoyance as well as serious loss of time and money.

Claim.

I claim, and desire to secure by Letters Patent—
The tail or projection T, upon the rotating hook of a sewing-machine, constructed and adapted to operate substantially as herein set forth.

JAK. HUSNIK.
